EXPANDING CHISEL

Eugene Brehmer, St. James, Minn.

Application October 29, 1947, Serial No. 782,788

2 Claims. (Cl. 254—91)

1

This invention relates to an expanding chisel. It is an object of the present invention to provide a chisel which may be used for the removing of baseboards and casings which can be expanded to separate the same from the building wall and whereby such operations can be effected without damage to either the wall or the board.

Other objects of the present invention are to provide an expanding chisel which is of simple construction, easy to operate, inexpensive to manufacture, durable, compact and efficient in operation.

For a better understanding of the invention, reference may be had to the following detailed description taken in connection with the accompanying drawing, in which

Fig. 1 is a perspective view of the chisel embodying the features of the present invention.

Fig. 2 is a longitudinal cross-sectional view taken through the chisel with the expanding bar in its lowered position.

Fig. 3 is a longitudinal sectional view of the chisel with the expanding bar elevated.

Fig. 4 is a top plan view of the chisel with the expanding bar elevated.

Figs. 5 and 6 are respectively transverse sectional views taken on lines 5—5 and 6—6 of Fig. 3.

Referring now to the figures, 10 represents the main blade of the chisel which has a cutting edge 11 and a rearwardly and upwardly inclined integral handle rod 12. The main part or blade 10 has a longitudinally-extending slot 13 for the reception of an expanding bar 14 and links 15 by which the bar 14 is connected to the blade 10 for movement into and out of the slot 13. The links 15 are arranged in pairs and are pivoted to the opposite sides of the slot 13. Recesses 16 are provided in the sides of the slot 13 and receive the links 15. Screws 17 attach the links to the blade 10 and the bar 14.

The forward end of the bar 14 is beveled as indicated at 18 to fit beveled end 19 of the slot 13 of the blade. On the handle 12 there is fixed a U-shaped member 21 by weld 22. This member 21 has separated upstanding projections through which extend a pivot pin 23 to connect an operating handle 24 theeto. This operating handle 24 has a downwardly bent forward end and rises above the raised integral handle 12 of the blade 10.

The bar 14 has an upwardly and rearwardly inclined or bent portion 25 with a narrow section 26 adapted to receive operating links 27 connected to the operating handle 24 by a pivot pin 28. The links 27 are connected with the section 26 by a pivot pin 29.

In operation the chisel is inserted between a wall and a baseboard while the bar 14 is within the slot 13. When once fully in rear of the base-

2

board, the operating handle 24 can be depressed so as to cause the bar 14 to be elevated out of the slot 13 and effect a lifting action upon the baseboard being removed from the wall. This operation can be effected with little more difficulty than with a straight chisel and neither the board nor the wall will be bruised or damaged.

While various changes may be made in the detail construction, it shall be understood that such changes shall be within the spirit and scope of the present invention as defined by the appended claims.

I claim:

1. In an expanding chisel, a main blade provided with a longitudinally extending slot, an inclined handle rod projecting rearwardly from said main blade, an expanding bar mounted for movement into and out of said slot, a plurality of links pivotally connecting said expanding bar to said main blade, an upwardly and rearwardly inclined portion projecting from said expanding bar, said inclined portion terminating in a narrow section, an operating handle pivotally connected to said handle, and means for pivotally connecting said operating handle to said narrow section.

2. In an expanding chisel, a main blade provided with a longitudinally extending slot, an inclined handle rod projecting rearwardly from said main blade, an expanding bar mounted for movement into and out of said slot, a plurality of links pivotally connecting said expanding bar to said main blade, there being a plurality of spaced recesses arranged in said main blade for receiving said links when said expanding bar is positioned in said slot, an upwardly and rearwardly inclined portion projecting from said expanding bar, said inclined portion terminating in a narrow section, an operating handle pivotally connected to said handle rod, and means embodying a pair of links for pivotally connecting said operating handle to said narrow section.

EUGENE BREHMER.
